UNITED STATES PATENT OFFICE.

JAMES W. McCABE, OF NEW YORK, N. Y.

DESIGN FOR A PHOTOGRAPHIC MOUNT.

SPECIFICATION forming part of Design No. 34,809, dated July 23, 1901:

Application filed May 17, 1901. Serial No. 60,773. Term of patent 3½ years.

To all whom it may concern:

Be it known that I, JAMES W. McCABE, a citizen of the United States, and a resident of the borough of Manhattan, in the city of New York, in the county of New York and State of New York, have invented and produced a new and original Design for a Photographic Mount, of which the following is a specification.

The design relates to the surface ornamentation of the cardboard; and it consists of a border composed of a series of groups of three elements following each other in regular succession all around, the said elements comprising, as shown, a cluster of dots, a spray, and a scroll, marked, respectively, 1, 2, and 3.

What I claim as new, and desire to secure by Letters Patent, is—

The design for a photographic mount, substantially as herein shown and described.

Signed at the borough of Manhattan, in the city of New York, in the county of New York and State of New York, this 16th day of May, A. D. 1901.

JAMES W. McCABE.
